UNITED STATES PATENT OFFICE

WILLIAM F. KIESEL, JR., OF HOLLIDAYSBURG, PENNSYLVANIA

LOCOMOTIVE FRAME

Application filed April 17, 1930. Serial No. 445,004.

This invention relates particularly to integral or one-piece cast frames for electric locomotives, though some features of the invention may obviously be applied to other types of locomotives.

The principal object of the invention is to include in a one-piece locomotive frame a number of tanks for the accommodation, for example, of water, oil and compressed air, these tanks being so arranged and fabricated as to conform with the essential requirements of electric locomotive frames as to wheel spacing, the location of motors, brake gear, spring-rigging and other equipment to which paramount consideration must be given, and the constituent parts of the tanks being so incorporated in the frame as to produce a structure of minimum weight in proportion to strength and rigidity.

One specific object of the invention is to provide in an integral cast frame for an electric locomotive a support for a heating boiler, the support serving also as the top of a water storage compartment.

Another specific object is to provide in a frame of this character means for the support of sand cores used in fabricating the tanks which have been referred to, and means whereby the cores can be readily removed from the tanks after the casting has been completed.

Another specific object is to provide in such a frame main longitudinal side members, portions of which serve as walls for water storage tanks and as walls for cylindrical tanks disposed outside the frame.

Another specific object is to provide in such a frame a series of cross-ties or transverse members connecting the longitudinal side members at points intermediate their ends and serving, for example, as walls for water storage compartments, as supports for the suspension of motors, as bolsters and as supports for various locomotive equipment, said cross-ties being so designed and disposed with respect to the side frames as to produce a compact and rigid structure characterized by advantages which will be readily apparent to those skilled in this art.

A detailed description, which has reference

to the accompanying drawings illustrating one embodiment of the invention, follows. Of the drawings:

Fig. I is a top view of one end of an electric locomotive frame embodying the invention. 55

Fig. II is a top plan view of the other end of the frame shown in Fig. I, the views of Figs. I and II forming a complete plan view of the frame. 60

Fig. III is a side elevation of the part of the frame shown in Fig. I.

Fig. IV is a side elevation of the part of the frame shown in Fig. II.

Fig. V is an enlarged longitudinal section of the frame, taken on the line V—V of Fig. I. 65

Fig. VI is an enlarged longitudinal section of the frame, taken on the line VI—VI of Fig. II.

Fig. VII is an enlarged end view of the frame with a part shown in section, taken on the line VII—VII of Fig. I. 70

Fig. VIII is an enlarged cross-section of the frame taken on the line VIII—VIII of Fig. I.

Fig. IX is an enlarged cross-section of the frame taken on the line IX—IX of Fig. I. 75

Fig. X is an enlarged cross-section of the frame taken on the line X—X of Fig. I.

Fig. XI is an enlarged cross-section of the frame taken on the line XI—XI of Fig. I. 80

Fig. XII is an enlarged cross-section of the frame taken on the line XII—XII of Fig. II.

Fig. XIII is an enlarged cross-section of the frame taken on the line XIII—XIII of Fig. II. 85

Fig. XIV is an enlarged cross-section of the frame taken on the line XIV—XIV of Fig. II; and, 90

Fig. XV is an enlarged end view of the frame with a part shown in section taken on the line XV—XV of Fig. II.

The locomotive frame as illustrated comprises an integral piece including generally a pair of main longitudinal side members 1, and a series of transverse members 2, 3, 4, 5, 6, 7, 8, 9 and 10 connecting the side members 1 at their ends, and at points intermediate their ends. 95

For convenience the constituent parts of the frame are hereinafter described with reference initially to the front end of the frame shown at the left hand of Fig. I, and thereafter proceeding along the frame to the right hand of Fig. II.

With particular reference to Figs. I and VII, it will be seen that the longitudinal side members 1 converge slightly toward the end 10 of the frame, terminating in the transverse wall 2 above an end-frame section 11 which acts as a draft gear housing. The side members 1 are also integrally connected at this end of the frame by bottom plates 12, top 15 plates 13 formed to accommodate a heating boiler at 14, and the stiffening member 4, these members 1, 2, 12, 13 and 4 forming an end compartment 50 for water storage extending from one side of the frame to the other. Suitable openings in the top of the 20 water storage compartment 50 are provided at 15 and 16 to give ready access to the compartment and to enable the filling of it with water and the withdrawal of water therefrom.

Additional openings 17 at the side members 1 are provided so that sand cores may be supported within the water compartment during the casting operation and later removed 30 when the casting has been completed. The openings 17 are subsequently covered with plates and sealed to render the compartment water tight. At the bottom of the water compartment 50 and running longitudinally 35 thereof are a pair of parallel stiffening members 18 with openings 19 permitting the passage of water from one side to the other. At the top of the water compartment 50 and immediately beneath the heating boiler support 40 port 14, there is a longitudinal partition 20 running centrally of the frame, and forming a trough to accommodate chains passing from a hand brake chain shaft at 21 at the front of the boiler to the brake cylinders supported 45 on the pads 22.

Directly beneath the annular support 14 for a heating boiler there is a cross-tie 3 which serves also as a body bolster and has a center plate 23 adapted to bear upon the 50 front locomotive truck. As shown in Fig. VIII forward of the cross-tie 3 there is a transverse stiffening member 24 which transfers the weight of the boiler to the longitudinal side members 1. The combined weight of 55 side members 1 and heating boiler is transferred to the center plate 23 of the bolster 3 by diagonal stiffening members 25.

Disposed on either side of the water compartment at this end of the frame are two 60 cylindrical oil tanks 26. The longitudinal side members 1, which form the sole partition between the oil tanks 26 and the water compartment 50, have portions 27 of part cylindrical shape constituting a part of the walls 65 of the oil tanks 26 and of the water compartment. Diagonal braces 28 and 29 reinforce the longitudinal side members 1 at their portions which comprise the side walls of the water compartment. The oil tank walls are formed with cored openings 30 to permit the 70 escape of foundry gases during casting, these openings being subsequently closed by filling with cast steel welded in place or by welding plates over the openings. The oil tanks 26 are also cast with their forward ends 75 open, these ends being subsequently closed by reservoir heads 31. At the other end each tank has an opening 32 eccentric to its cylindrical wall. The openings at the ends of these tanks permit the support of sand cores 80 therein during the casting operation and the subsequent removal of the sand cores.

Between the cross-tie stiffening member 4, which also serves as an end wall for the water compartment, and the cross-tie 5 are the supports or pads 22 for the accommodation of 85 brake cylinders, and beneath the pads 22 is a webbed projection 33 comprising a bearing for the fulcrums of driver brake levers.

The intermediate frame section comprises 90 the longitudinal side members 1 and cross-ties 5, 6 and 7. Throughout this section the side members have portions of substantially box-shaped section as indicated at 34 with a superimposed angle member 35 having a 95 flange 36 turned inward. Flanges 37 formed at the top of the oil cylinders 26 and air cylinders 38, to be later referred to, are in the same plane as the top of the box-shaped portions of the side members 1, and these parts 100 together form a support for outside deck plates running longitudinally of the locomotive.

Cross-ties 5, 6 and 7 of the intermediate 105 frame section, as shown in detail in Figs. X, XI and XII, are provided with pads 39 for engaging motor nose clamps, the pads 39 being disposed to provide a three-point suspension for each electric motor frame. Each cross-tie 5, 6 and 7 is also provided with bifurcated brackets 40 for supporting the clog hangers of the driver brakes. Adjacent to the areas in which the motors are suspended the side frames 1 are provided with pedestals 41 for the axle journal boxes of the driving wheels, the bottom ends of the pedestals 41 being connected by longitudinal members 42 which are cross-connected by means of the cross-ties 5, 6 and 7.

At the rear end of the frame, as shown in 115 Figs. II and IV, the longitudinal side members 1 converge slightly, terminating in the end wall 10, above an end-frame portion 43 which comprises a draft gear housing similar to the draft gear housing 11 at the front end of the frame. A second water storage compartment 51 is formed at this end of the frame bounded by the longitudinal side members 1, the end wall 10, bottom plates 44, the 120

combined cross-tie and tank wall 8, and the top member 45.

- 5 The box-shaped cross-tie 8, which also acts as an end wall for the water compartment 51, is provided with depending perforated arms 46, as shown clearly in Fig. IV, adapted to carry fulcrum pins for spring-rigging equalizer beams which converge towards a cross-head guide which is positioned within 10 the cross-head guide support 47. Diagonal stiffening members 48 integrally connect the cross-tie 8 with the support 47 and form a cavity beneath the end of the water compartment through which equalizer beams pass to 15 the equalizer cross-head guide. A number of openings indicated at 49 in the walls of the box-shaped cross-tie 8 permit the passage of water to the wall 52 which forms the end of the water compartment 51.
- 20 The cross-tie 9 comprises the equalizer cross-head support 47 and stiffening plates 55 connecting the support 47 with the side members 1, there being a large opening 53 and a number of smaller openings 54 per- 25 mitting the passage of water from one side of the stiffening plates 55 to the other. A pair of parallel longitudinal stiffening mem- bers 56 provided with suitable openings 57 connect internally of the water compartment 30 51 the cross-head guide support 47 with the end wall 10. A number of openings 58, 59, 60 and 61 of various sizes and shapes in the top member of the water compartment 51 give ready access to the compartment and 35 provide means for filling the compartment and for withdrawing water therefrom. Ad- ditional openings 62 serve the same purpose as the corresponding openings 17 at the other end of the frame.
- 40 Compressed air tanks 38 are disposed at the sides of the water compartment 51 in a manner similar to that in which the oil tanks 26 are incorporated in the frame at the other end, and it will be apparent that 45 many other structural features of the rear end of the frame correspond to those already described with respect to the front end.

The entire structure illustrated in the drawings with the exceptions of the heads 50 31 and 63 for the cylindrical air and oil tanks comprises a one-piece integral casting so de- signed that the operation of assembling the complete locomotive equipment upon the frame is greatly simplified and the number 55 of fastening means, such as bolts, rivets and the like, normally required for assembling, is considerably reduced.

The frame possesses many structural ad- 60 vantages both with respect to the distribution of stresses and strains and with respect to strength and rigidity in proportion to the amount of metal used. Numerous joints and supports for equipment, normally made as separate parts and requiring drilling of the 65 frame and the use of fastening bolts, have

been incorporated in the casting with ob- vious attendant advantages.

While one specific embodiment of the in- 70 vention has been described in some detail, it will be apparent to those skilled in the art that various modifications and changes may be made in the form of the frame as described without departing from the spirit of the claims hereto appended. It will also be 75 apparent that certain features of the inven- tion may be used to advantage without a cor- responding use of other features.

Having thus described my invention, I claim:

1. A locomotive frame casting including, 80 in an integral piece, main longitudinal side members, bottom plates and transverse mem- bers connecting said side members and forming therewith an end compartment for liquid storage, occupying the full space between 85 said side members at the ends thereof.

2. A locomotive frame casting including, 90 in an integral piece, a draft gear housing, a superimposed main frame section comprising main longitudinal side members, and bottom plates and transverse members connect- 95 ing said side members and forming therewith an end compartment for liquid storage.

3. A locomotive frame casting including, 95 in an integral piece, longitudinal side mem- bers, cross-ties forming with said side mem- bers areas adapted to accommodate electric 100 motors, and transverse members and bottom plates forming with said side members end compartments for liquid storage.

4. A locomotive frame casting including, 105 in an integral piece, longitudinal side mem- bers, cross-ties forming with said side mem- bers areas adapted to accommodate electric 110 motors, a transverse body bolster adapted to bear upon a locomotive truck, and addi- tional transverse members connecting said side members and forming therewith a liquid storage compartment above said locomotive truck.

5. A locomotive frame casting including, 115 in an integral piece, longitudinal side mem- bers, cross-ties forming with said side mem- bers areas adapted to accommodate electric 120 motors, a transverse body bolster adapted to bear upon a locomotive truck, and addi- tional transverse members connecting said side members and forming therewith a liquid storage compartment above said locomotive truck, said transverse body bolster having 125 openings therein permitting the passage of liquid from one side to the other.

6. A locomotive frame casting including, 125 in an integral piece, longitudinal side mem- bers, bottom and transverse members forming therewith a compartment for liquid storage, and cylindrical tanks outside said longitudi- 130 nal side members.

7. A locomotive frame casting including, 135

- in an integral piece, longitudinal side members, bottom and transverse members forming therewith a compartment for liquid storage, and cylindrical tanks outside said longitudinal side members, said side members forming the sole partition between said storage compartment and said cylindrical tanks. 70
8. A locomotive frame casting including, in an integral piece, a longitudinal side member, and a cylindrical tank supported wholly upon said side member, said side member having a part cylindric area forming a portion of the wall of said tank. 75
9. A locomotive frame casting, including, in an integral piece, main longitudinal side members, members connecting said side members and forming therebetween a compartment for liquid storage, a cylindrical tank disposed outside of one of said side members, 80
- 20 said side member having a part cylindric area forming a portion of the wall of said tank and forming the sole partition between said storage compartment and said cylindrical tank. 85
10. A locomotive frame casting including, in an integral piece, longitudinal side members, and members connecting said side members and forming therebetween a compartment for liquid storage, the member forming 90
- 30 the top of said compartment comprising a support for a heating boiler. 95
11. A locomotive frame casting including, in an integral piece, longitudinal side members, members connecting said side members 100 and forming therebetween a compartment for liquid storage, and tanks disposed outside said longitudinal side members, the member forming the top of said liquid storage compartment comprising a support for a heating 105
- 40 boiler adapted to be accommodated between said outside tanks. 110
12. A locomotive frame casting including, in an integral piece, a water storage compartment, tanks disposed at the sides of said 115
- 45 compartment, portions of the side walls of said compartment comprising portions of the walls of said tanks, and the top of said compartment comprising a support for a heating 120
- 50 boiler. 125
13. A locomotive frame casting including, in an integral piece, a liquid storage compartment, and a partition forming a trough in the top of said compartment separated from said liquid storage space, said trough being adapted to accommodate hand brake chains. 130
14. A locomotive frame casting including, in an integral piece, longitudinal side members, members connecting said longitudinal 135
- 55 side members and forming therebetween a liquid storage compartment, brake cylinder pads adjacent said storage compartment, and a partition forming a trough in said storage compartment separated from the liquid storage space, said trough being adapted to accommodate brake gear leading to said brake cylinders. 140
15. A locomotive frame casting including, in an integral piece, longitudinal side members, members connecting said side members and forming therebetween a liquid storage compartment, the member forming the top of said compartment comprising also a support for a heating boiler, brake cylinder pads adjacent said storage compartment, and a partition forming a trough in said storage compartment separated from the liquid storage space, said trough being adapted to accommodate brake gear leading from the front of the heating boiler to the brake cylinders. 145
16. A locomotive frame casting including, in an integral piece, longitudinal side members, and members connecting said side members and forming therewith walls of a compartment for liquid storage, said walls having openings therein whereby sand cores may be supported in said compartment and removed therefrom. 150
17. A locomotive frame casting including, in an integral piece, a water storage compartment, a cylindrical tank disposed adjacent said compartment with part of the wall of said tank forming part of the wall of said compartment, said tank and compartment having means permitting the support of sand cores therein and the removal of the sand cores after the casting is completed. 155
18. A locomotive frame casting including in an integral piece, a longitudinal side member, and a cylindrical tank disposed along 160
- said side member, said tank having means at the ends thereof permitting the support of sand cores therein and the removal of the sand cores after the casting is completed. 165
19. A locomotive frame casting, including in an integral piece, main longitudinal side members, a member connecting said side members and comprising a support for a heating boiler, a transverse stiffening member for transferring the weight of the boiler to the 170
- side members, and a bolster connecting said side frames beneath said heating boiler and adapted to bear upon a truck. 175
20. A locomotive frame casting, including in an integral piece, main longitudinal side members, a member connecting said side members and comprising a support for a heating boiler, a bolster connecting said side frames beneath said heating boiler, said bolster having a center plate adapted to bear upon a truck, and diagonal members for transferring the combined weight of heating boiler and longitudinal side members to said center plate. 180
21. A locomotive frame casting, including in an integral piece, main longitudinal side members, and transverse cross-ties connecting said side members, a number of said cross-ties serving as supports for electric motors and 185

- others serving as end walls for a liquid storage compartment.
22. A locomotive frame casting, including in an integral piece, main longitudinal side members, a cross-tie connecting said side members and serving as an end wall for a liquid storage compartment, a box-shaped cross-tie serving as a support for an electric motor, and a longitudinal member connecting said aforementioned cross-ties and serving as a brake cylinder support.
23. A locomotive frame casting, including in an integral piece, longitudinal side members having portions of box-shaped section, tanks alongside said side members, and flanges on said tanks in the same plane as the top of said box-shaped portions of said side members.
24. A locomotive frame casting, including in an integral piece, longitudinal side members, and a transverse cross-tie for carrying spring-rigging equalizer fulcrums, said cross-tie serving as an end wall for a liquid storage compartment.
25. A locomotive frame casting, including in an integral piece, main longitudinal side members, and cylindrical tanks disposed along said side members, said side members having portions of substantially box-shaped section and other portions of part-cylindric shape forming part of the walls of said tanks.
26. A locomotive frame casting, including in an integral piece, main longitudinal side members, members connecting said side members and forming therewith a compartment for liquid storage, and a transverse stiffening member within said compartment including an equalizer cross-head guide support and openings permitting the passage of a liquid from one side of said stiffening member to the other.
27. A locomotive frame casting, including in an integral piece, longitudinal side members, cross-ties connecting said side members and forming therewith areas in which electric motors are adapted to be supported, transverse members connecting said side frames and forming end compartments for liquid storage, a truck center plate beneath one of said compartments, and equalizer supports beneath the other of said compartments.
28. A locomotive frame casting, including in an integral piece, longitudinal side members, water storage tanks at the ends of said side members, oil tanks disposed at the sides of one of said water tanks, and air tanks disposed at the sides of the other of said water tanks, said longitudinal side members forming a part of the walls of said water, oil and air tanks.
29. A locomotive frame including, in an integral piece longitudinal side members, and cylindrical tanks disposed oppositely out-side said side members and supported there-
- on, said side members having part cylindric areas forming portions of the walls of said tanks.
- In testimony whereof, I have hereunto signed my name at Altoona, Pennsylvania, 70 this 14th day of April, 1930.
